US00D662882S

(12) **United States Design Patent**
Wu

(10) **Patent No.:** **US D662,882 S**
(45) **Date of Patent:** **** Jul. 3, 2012**

(54) **BATTERY CASING**

(75) Inventor: **Ming Wai Leo Wu**, Tseung Kwan O (HK)

(73) Assignee: **Acolyte Technologies Corporation**, New York, NY (US)

(**) Term: **14 Years**

(21) Appl. No.: **29/398,581**

(22) Filed: **Aug. 2, 2011**

(51) **LOC (9) Cl. 13-02**

(52) **U.S. Cl. D13/119**

(58) **Field of Classification Search** D13/102-106, D13/110, 118-120, 184; 429/96-100, 163, 429/176

See application file for complete search history.

(57) **CLAIM**

The ornamental design for a battery casing, as shown and described.

DESCRIPTION

FIG. 1 is a top, front and left side perspective view of a battery casing showing our new design;

FIG. 2 is a bottom, rear and right side perspective view thereof;

FIG. 3 is a right side elevational view thereof, the left side elevational view being a mirror image;

FIG. 4 is a front elevational view thereof;

FIG. 5 is a rear elevational view thereof;

FIG. 6 is a top plan view thereof; and

FIG. 7 is a bottom plan view thereof; and,

FIG. 8 is an alternate top, front and left side perspective view of the battery casing.

The broken lines shown in the drawings are included for the purpose of illustrating environmental structure and form no part of the claimed design.

1 Claim, 5 Drawing Sheets
